Primary Examiner—Clare E Heflin(74) *Attorney, Agent, or Firm*—John F. Salazar; Middleton & Reutlinger(57) **CLAIM**

The ornamental design for a luminaire, as shown and described.

DESCRIPTION

FIG. 1 is a lower perspective view of the luminaire of the present invention;

FIG. 2 is an upper perspective view of the luminaire of the present invention;

FIG. 3 is a top view of the design of the present invention;

FIG. 4 is a rear view of the design of the present invention;

FIG. 5 is a front view of the design of the present invention;

FIG. 6 is a right side view of the design of the present invention; and,

FIG. 7 is a left side view of the design of the present invention.

The broken lines showing environmental structure are for illustrative purposes only and form no part of the claimed design.
